US0D1042611S

(12) **United States Design Patent** (10) **Patent No.:** **US D1,042,611 S**
(45) **Date of Patent:** **** Sep. 17, 2024**

(54) **EYEGLASSES**

(71) Applicant: **HSIEN CHANG OPTICAL INDUSTRIAL CO., LTD.**, Tainan (TW)

(72) Inventor: **Wen-Hsiung Chou**, Tainan (TW)

(73) Assignee: **HSIEN CHANG OPTICAL INDUSTRIAL CO., LTD.**, Tainan (TW)

(**) Term: **15 Years**

(21) Appl. No.: **29/884,620**

(22) Filed: **Feb. 14, 2023**

(51) **LOC (14) Cl.** **16-06**

(52) **U.S. Cl.**

USPC **D16/326**

(58) **Field of Classification Search**

USPC D16/300, 324, 326, 328, 335, 336;
D24/110.1, 110.2; D29/104, 105, 106

CPC G02C 7/16; G02C 5/143
